UNITED STATES PATENT OFFICE

PAUL MORTON BELLOWS, OF GLENDALE, CALIFORNIA

APPARATUS FOR APPLYING DRAFT GEARS TO RAILROAD CARS

Application filed September 8, 1930. Serial No. 480,599.

This invention relates to an apparatus particularly adapted to apply draft gears to railroad cars.

Railroad cars of all classes are equipped with draft gears, these gears are interconnected with the couplers of the car and serve as a shock absorber while making up a train.

At present when it becomes necessary to replace one of these gears, the car is raised with jacks, and the truck under said gear moved to one side, this procedure necessarily requires considerable time and labor, especially so when handling heavily loaded freight cars.

15 The object of this invention is to provide an apparatus of the character described constructed in such a manner that a draft gear may be applied or removed from a railroad car without the employment of jacks.

20 Another object of the present invention is to provide an apparatus in which a draft gear placed thereon is raised into position (for connection with the car frame) by fluid pressure means.

25 Other objects and advantages will be apparent from the following description, reference being had to the accompanying drawings, in which—

Fig. 1 is a top plan view of the apparatus according to the present invention.

Fig. 2 is a side elevation.

Fig. 3 is a longitudinal section taken on line 3—3 of Fig. 1.

Fig. 4 is an elevation of one end of the apparatus.

Figs. 5, 6, 7 and 8 are views showing the successive steps employed in the operation of applying a draft gear to a railroad car with the improved apparatus, the views showing the apparatus and car in side elevation, parts being broken away and shown in section.

Referring now more particularly to the drawings, the present apparatus consists of 45 a frame 16 formed from channel irons, and

supported on a pair of wheels 12 journalled on axles 13 secured to a pair of vertically disposed bearings 14 formed on the ends of a metal strap bar 15, said bar being secured to the lower flanges of the side channels of the frame 16.

A trailer guide wheel 18 is mounted on an axle 19 carried by a fork 20, having a king pin 21 pivotally mounted in bearings 22 of a supporting arm 23 secured to cross member 24 of the frame.

Secured to the side members of the frame adjacent to the guide wheel 18 is a pair of standards 26 which serve to support a cylinder 27 that is pivotally mounted on a rod 29 extending through an opening in a lug 30 formed on the cylinder head 31, and through openings in the upper ends of the standards.

Mounted in the cylinder is a piston 32 having a rod 33, the rod extending through an opening 34 in a guide plate 35 secured to the lower end of the cylinder, and is connected by a clevis 36 and a pin 37 to the outer end of a bar 38. The bar is pivotally mounted on a pin 40 secured to uprights 42 which are connected to the side members of the frame 16.

A member generally designated at 44 is pivotally mounted on a rod 45, which extends through openings in the upper ends of the uprights and openings in the side rails 46 of said member.

One end of the member 44 is connected to the bar 38 by a link 48, the upper end of which is mounted on a rod 49 which extends between and is secured to the rails 46, the lower end of the link being connected to the bar 38 by a pin 50. The opposite end of the member 44 is connected to the bar 38 by arms 51 formed on a platform 52 adapted to support the draft gear generally designated at D, and the upper ends of the arms are pivotally mounted on a rod 53 extending between the rails, the lower ends thereof being

connected to the bar by a pin 54 disposed in an arcuate slot 55 formed in said bar.

One end of a link 58 is mounted on the pin 54, and the opposite end thereof is connected by a pin 61 to a crank 60 pivotally mounted on the bar 38, the link and crank serve to tilt the platform for a purpose later described.

Platform 52 consists of a center bar 62, 10 side plates 63, an end plate 64, and an upright 65. It will be seen, due to the parallel mounting of the bar 38 and member 44, that the platform lies in a horizontal plane regardless of the position assumed by said 15 bar and member i. e., when the platform is raised or lowered.

When mounted on the platform the plates 63 engages the sides of the draft gear, and prevent sidewise tilting, the upright extends 20 between the flanges 75 of the coupling receiving member, and a removable pin 76 inserted through the slots 77 formed therein, and an opening 78 in the upper end of the upright serves to hold the gear against rocking or 25 tilting.

The platform is raised by admitting compressed air into the cylinder above the piston. A pipe line 70 with intake and exhaust valves 71 and 72 respectively are provided 30 for this purpose, the pipe entering a port 73 formed in the cylinder wall, and a flexible hose 74 extends from the pipe to a source of compressed air.

The platform is now raised (by opening 35 of the intake valve 71) so that the bar 38 will be clear of the ground, the valve is then closed and the apparatus moved under the car designated at C. The platform is then lowered (by opening the exhaust valve 72) 40 and tilted as shown in Fig. 6 by manipulating the crank 60, the platform being thus tilted in order that the outer end of the draft gear will clear the axle A of the truck T.

The platform is then raised and returned 45 to a horizontal position and the apparatus moved to a position so that the draft gear will be directly under the flanges or lugs L secured to center sills S of the car frame as 50 shown in Fig. 7, and the draft gear is raised to the position shown in Fig. 8 between the lugs L. The carrier plate P is then bolted to the center sills, and the pin 76 removed.

The platform may then be lowered and 55 the apparatus removed. It will be readily understood that a draft gear may be removed by reversal of the above described operations, at which time lowering of the gear may be controlled by adjusting the exhaust valve.

I claim:

1. An apparatus of the character described comprising a horizontally disposed wheeled frame, a pair of longitudinal elevating members pivotally mounted on said frame substantially midway thereof in spaced relation,

a link connecting said members together adjacent one end thereof and holding the same in parallel relation, a load supporting platform, link means pivotally connecting said platform to said elevating members, whereby the platform will assume a horizontal position when the same is raised or lowered by tilting movement of said members, and a fluid operated means mounted on said frame and pivotally connected to the elevating member for tilting the same.

2. An apparatus of the character described comprising a rectangular shaped frame, wheels supporting said frame, an upright secured to each side of said frame, a bar pivotally mounted on a pin extending between said uprights, a member disposed above said bar pivotally mounted on said uprights, a link connected to said bar and member at one end thereof, and holding the same in parallel relation, a platform having a pair of arms formed thereon, means connecting the arms on said platform to said bar and member, and means carried by said frame and connected to said bar, whereby said platform may be raised.

3. An apparatus of the character described comprising a rectangular shaped frame, wheels supporting said frame, an upright secured to each side of said frame, a bar pivotally mounted on a pin extending between said uprights, a member disposed above said bar pivotally mounted on said uprights, a link connected to said bar and member at one end thereof and holding the same in parallel relation, a platform having a pair of arms formed thereon, means connecting the arms on said platform to said bar and member, a cylinder carried by said frame, a piston in said cylinder having a rod connected to said bar, and means for admitting compressed air into said cylinder above the piston, whereby said platform may be raised.

4. In an apparatus of the character described, a horizontally disposed frame mounted on wheels, a pair of longitudinal members pivotally connected to said frame, means connecting said longitudinal members together at one end thereof and holding the same in parallel relation, a platform having arms depending therefrom engaging the opposite ends of said longitudinal members and pivotally connected to the uppermost of said members, and means connected to the arms of said platform and the lowermost longitudinal members, whereby said platform may be tilted.

5. In an apparatus of the character described, a horizontally disposed frame mounted on wheels, a pair of longitudinal members pivotally connected to said frame, means connecting said longitudinal members together at one end thereof and holding the same in parallel relation, a platform having arms depending therefrom engaging the op-

posite ends of said longitudinal members, a pin pivotally connecting said arms to the uppermost of said longitudinal members, a pin connected to the arms of said platform and extending through an arcuate slot in the lowermost longitudinal member, a crank carried by the lower longitudinal member and a link connected to said pin and crank, whereby said platform may be tilted,

10 In testimony whereof I affix my signature.
